US0D1066317S

(12) **United States Design Patent** (10) **Patent No.:** **US D1,066,317 S**
(45) **Date of Patent:** **** Mar. 11, 2025**

(54) **KIOSK PANEL**

(71) Applicant: **Capital One Services, LLC**, McLean, VA (US)

(72) Inventor: **David Kelly Wurmfeld**, Palm Bay, FL (US)

(73) Assignee: **Capital One Services, LLC**, McLean, VA (US)

(**) Term: **15 Years**

(21) Appl. No.: **29/792,540**

(22) Filed: **Apr. 6, 2022**

(51) LOC (15) Cl. **14-02**

(52) U.S. Cl.

USPC **D14/307; D18/4.4**

(58) **Field of Classification Search**

USPC D10/42; D14/126, 299, 307, 308, 336, D14/371, 373, 374, 447, 900, 901, 902; D18/3.1, 3.2, 3.3, 4.1, 4.2, 4.3, 4.4, 4.5, D18/4.6; D20/1, 2, 3, 4, 5, 6, 8; D21/370, 325; D99/28, 33

(57) **CLAIM**

The ornamental design for a kiosk panel as shown and described.

DESCRIPTION

FIG. 1 is a front right perspective view of a kiosk panel showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom view thereof.

The broken lines shown in FIGS. 1 and 3-7 illustrate portions of the kiosk panel that form no part of the claimed design.

1 Claim, 4 Drawing Sheets
